CLAIM

The ornamental design for a skid-steer loader, as shown and described.

DESCRIPTION

FIG. 1 is a front, left-side, and top view of a skid-steer loader, showing the new design.

FIG. 2 is a top plan view of the skid-steer loader.

FIG. 3 is an enlarged front elevation view of the skid-steer loader.

FIG. 4 is a left-side elevation view of the skid-steer loader.

FIG. 5 is an enlarged rear elevation view of the skid-steer loader.

FIG. 6 is a right-side elevation view of the skid-steer loader; and,

FIG. 7 is a bottom plan view of the skid-steer loader.

The broken lines represent elements of the skid-steer loader that do not form part of the claimed design.
